DESIGN FOR A WOOD FASTENER

Nesbit A. Boyles, Hartford City, Ind.

Application June 21, 1943, Serial No. 110,497

Term of patent 14 years

To all whom it may concern:

Be it known that I, Nesbit A. Boyles, a citizen of the United States, residing at Hartford City, in the county of Blackford and State of Indiana, have invented a new, original, and ornamental Design for Wood Fasteners, of which the following is a specification, reference being had to the accompanying drawing, forming a part thereof.

Figure 1 is an elevational view showing one side of a wood fastener, showing my new design.

Figure 2 is a similar elevational view showing the opposite side of the wood fastener.

Figure 3 is a side edge view.

Figure 4 is a top edge view.

Figure 5 is a perspective view.

I claim:

The ornamental design for a wood fastener, as shown.

NESBIT A. BOYLES.
